UNITED STATES PATENT OFFICE.

ALFRED E. JONES, OF NEWARK, NEW JERSEY, ASSIGNOR TO HIMSELF,
JOHN T. ROWLAND, AND ROBERT GRAY, JR., OF SAME PLACE.

SETTLING-TANK.

SPECIFICATION forming part of Letters Patent No. 251,717, dated January 3, 1882.

Application filed June 25, 1881. (No model.)

To all whom it may concern:

Be it known that I, ALFRED E. JONES, of Newark, in the State of New Jersey, have invented a new Settling-Tank, of which the following is a specification, reference being had to the drawings accompanying the same.

My invention consists in the combination of partitions, hereinafter described, with a tank, in the bottom of which are openings between 10 each partition, whereby the sediment may be drawn off and each opening or slot supplied with a revolving disk, whereby the opening may be closed or exposed, as hereinafter described.

15 My invention is more especially adapted for use in mixing colors in potters' uses, refining clay, and recovering dyes when precipitating agents are employed, and when it is desired to draw off the heavier particles and the precipi- 20 tants.

In an application simultaneously herewith made I use this settler for the purpose of separating the heavier particles of ore, &c., from the lighter-weighted gold, and the gold floating in the liquid is drawn off and subsequently 25 treated as therein stated.

I will now describe my settling tank.

Figure 1 is plan view of my tank settler, and Fig. 2 is a section of the same.

30 A is the tank proper, and is of the desired size.

B B' B² B³ B⁴ B⁵ are partitions situated at right angles to the bottom of the tank, which bottom is a flat plane surface. These uprights 35 are so constructed at about their center as to form the bulb, the upper half being like the lower half and of slanting sides.

C C' C² C³ C⁴ C⁵ C⁶ are three-quarter disks, the remaining quarter being cut away except 40 the center. These are revolved on their axles b b' b² b³ b⁴ b⁵ b⁶, and so formed that when they are shut back against the under hollow part of the partition B as to shut off all communication or access to the bottom of the tank, but 45 allowing all sediments or liquids in the box to flow or fall down upon them.

o o' o² o³ o⁴ o⁵ o⁶ are openings or holes in the bottom of the tank, and are constantly left open.

a² is an induct and a' an educt pipe, situated about three-quarters up the side ends of the 50 tank A.

L is a drawer situated underneath the tank A and the openings o therein, into which falls all that is turned out. These openings may have valves to them, so that they are not constantly left open.

The operation of my machine is as follows: Suppose I wish to separate the heavier part of the precious metal from sand-tailings, &c. The ore or sand-tailings coming from a common pug-mill or quartz-crusher is led, with sufficient water, through the pipe a² into the tank A. As soon as the first partition is full the second becomes filled, and so on till the whole tank is filled up. Then being allowed 65 to stand, the disk remaining as shown in the drawings, the heavier particles all settle to the bottom through the opening where the disk is cut away. When sufficiently settled the liquid, with its float, is drawn off through the 70 pipe a' into a receptacle. Now turn the disks over so that their curved sides cover the entire distance between the uprights or separators B B', and it will readily be seen that the sediment will pass through or can be pulled through 75 the openings into the drawer L and put again into the pug-mill or crusher. All this is done without interfering with the operation of the machine.

It will readily be seen that this settler can 80 be employed in precipitating dyes, &c., also for potters' uses.

What I claim, and desire to secure by Letters Patent, is—

The tank A, provided at its bottom with openings o, and having partitions B, said partitions having inclined and curved portions, as shown, in combination with the segmental disks C, substantially as described, and for the purpose specified.

ALFRED E. JONES.
